(57) **CLAIM**

The ornamental design for a shaving razor stand.

DESCRIPTION

FIG. 1 is a top, rear, and right side perspective view of a shaving razor stand showing our new design;
FIG. 2 is a rear elevational view thereof;
FIG. 3 is a top plan view thereof;
FIG. 4 is left side elevational view thereof;
FIG. 5 is a front elevational view thereof;
FIG. 6 is a bottom plan view thereof;
FIG. 7 is an additional top, rear, and right side perspective view thereof; and,
FIG. 8 is a top, front, and right side perspective view thereof.
The broken-line disclosure of a shaving razor in the views is for illustrative purposes only and forms no part of the claimed design.
